UNITED STATES PATENT OFFICE.

WILLIAM FORRESTER, JAMES FORRESTER, AND JOHN FORRESTER, OF LARBERT,
SCOTLAND.

MACHINE FOR FILLING BOTTLES WITH AERATED WATERS.

No. 927,228.

Specification of Letters Patent.

Patented July 6, 1909.

Application filed April 13, 1908. Serial No. 426,847.

To all whom it may concern:

Be it known that we, WILLIAM FORRESTER, JAMES FORRESTER, and JOHN FORRESTER, all subjects of the King of Great Britain, residing in Larbert, Stirlingshire, Scotland, have invented a new and useful Machine for Filling Bottles with Aerated Waters and the Like, of which the following is a full and complete specification.

10 The present invention relates to improvements in machines for filling bottles with aerated waters, and the like, the machine being of that type in which the filling devices are mounted on a table rotated by 15 power, or hand, the object being to simplify the construction of such machines, render them more automatic, and to provide an improved device for regulating the amount of liquid supplied to the bottle, whereby the 20 operation known as "snifting" is obviated.

We are aware that it has heretofore been proposed in the construction of machines forming the subject matter of the present invention to form the filling head or cup for 25 receiving the mouth of the bottle in one with the valve chamber containing the valve for controlling the supply of fluid, while others have been arranged with the filling head and valve chamber separate, in both cases, however, the valves are either operated by hand or by a large plate carrying a series of cams adapted to open and close such valves at predetermined periods, but this form of device is objectionable in that should a bottle 30 break, the liquid being supplied must flow away and be lost until the operator closes same by hand, or a cam comes into position to close the valve; in the latter case, however, unless the whole machine is stopped, or a new 35 bottle immediately placed in the machine, the liquid would again flow to waste when another cam opened the valve. In this form of machine it is also necessary to have a bottle in each holder while the machine is in motion, otherwise the fluid would go to waste each 40 time the valve of the particular empty holder was opened. Means have also been proposed for normally maintaining the supply valves closed or for automatically closing such valves 45 50 should a bottle break, such means being operated in some cases by devices connected to the bottle holder, while others have been operated by means contained in the filling head itself.

55 Means have heretofore been proposed for

regulating the amount of fluid supplied, thereby obviating the operation of snifting, consisting of a chamber placed between the valve and the mouth of the bottle, having a piston, formed of cup leathers, sliding therein carried by a screwed piston rod operated from the top of the cylinder, the cylinder has, however, to be of small diameter and of some length owing to the restricted position and close proximity of the discharge valves, thus necessitating a considerable movement of the piston rod to effect any appreciable alteration in the capacity of the cylinder, and, should the cup leathers get dry, leakage of air results.

The present invention broadly consists in providing each valve controlling a discharge opening with a separate cam plate, providing means for automatically operating such cam plates, means for automatically closing any one or more of such valves should a bottle be broken, or if a particular filler be vacant, and an improved form of chamber for regulating the amount of liquid supplied.

More particularly the invention consists in arranging the valve controlling the discharge of the fluid in the filling head itself, and the top of the head is shaped so as to permit a cam plate to freely rotate thereon when the same is automatically operated by means, such as a suitably supported roller, carried by the machine, such cam plate carrying a radially arranged roller adapted to operate in the manner hereafter described. The spindle of the valve, which operates vertically in a suitable box at the side of the filling head connected to the main supply pipe of the machine, passes through a suitable stuffing box, and is adapted to be actuated in the manner hereafter described by the roller carried by the cam plate only when a bottle is in position in the holder.

In the accompanying drawings which illustrate the invention:—Figure 1. shows diagrammatically the arrangement of the various parts of the machine. Fig. 2. a part sectional elevation of the filling head and bottle holder, the parts being shown in operative position. Fig. 3. a sectional elevation on line z—z of the filling head. Fig. 4. a part sectional side elevation showing the regulating chamber attached to the filling head. Fig. 5. a sectional elevation of a modified form of regulating chamber, and Fig. 6. a plan view of the cam plate.

- The machine, as illustrated, consists of the usual pedestal, or standard, A provided with a rotating table A¹. The top of the standard is provided with the distributing head A² which is connected to each of the filling heads d¹ as hereinafter described. A fixed frame A³ is provided, to which the supply pipe B is fixed, a flexible connection being arranged between the frame and the distributing head.
- 5 The frame A³ also carries the necessary cams for operating the valves.
- The bottle holder is of the usual construction, having a cup shaped part a, to receive the bottom of the bottle, carried by a suitable bracket b adjustably mounted on the standards c carrying the filling head d and regulating chamber e. To the lower part of the cup spindle f is pivoted a suitable lever g carried by the bracket b, a suitable spring h being arranged in the bracket so as to maintain the cup in its highest position and thus force the bottle into the aperture d¹ in the filling head d. A vertically arranged rod i is connected to the extreme end of the lever g, such rod being connected at its top end to a bell-crank lever j pivoted to the cross arm of standard c supporting the filling head d, a cam block or lever k provided with a wedge shaped slot l is connected to the other arm of the bell-crank lever j and adapted to rest on the top of the spindle m of the discharge controlling valve n, contained in chamber n¹, in such a manner that when the machine is in operation, the roller o of the cam plate p is caused to press on the top of the lever k and thereby depress the valve n and cause the liquid to flow to the bottle. When a bottle breaks, the bottle holder a is immediately returned to its highest position by means of spring h, the back end of the lever g connected thereto being lowered, and, at the same time, the lever k resting on the valve is, by means of its connections, automatically withdrawn to such a position that even 45 should the roller o come above same it will not operate the valve. The same conditions prevail when the holder is vacant and the filler out of action.
- If desired, instead of operating the bottle holder by hand it may be operated by foot, one means for effecting this being shown in Fig. 1, the lower end of the cup spindle f being formed with a hook f¹, or the like, adapted to engage a part f² carried by a foot lever f³ pivoted to the pedestal or standard A of the machine, suitable means, such as a balance weight f⁴, or spring, being provided for maintaining such foot lever in highest position.
- 50 The means for regulating the quantity of liquid supplied is carried by the standard c supporting the filling head d, and communicates therewith through a pipe e¹ and suitable screw down valve d². The regulator, as shown in Fig. 4, consists of a cylindrical

chamber e in which a fixed plunger e², carried by a hollow supporting stem e³, is adapted to slide. The supporting stem e³ is screw threaded and co-operates with the bottom of the chamber e so that when the chamber is rotated it is raised or lowered on its supporting stem. In order to provide an air tight joint between the plunger and the chamber when adjusted to the required height, the top of the stem may be slightly reduced as at e⁴ 75 so as to carry a plate e⁵ adapted to be forced down against an india rubber ring or washer e⁶ arranged above the fixed plunger e², whereby the same is squeezed against the side of the chamber e. The means for forcing the 80 plate downward may consist of a suitable shaped spindle e⁷ passing through a stuffing box e⁸ in the top of the chamber, a lock nut e⁹, or other suitable means, being formed on, or carried by its inner or lower end, adapted 85 to engage with a thread on the reduced part e⁴ of the supporting stem e³.

A modified form of regulator is shown in Fig. 5, and consists of the chamber e and fixed plunger e² carried by the hollow supporting stem e³ as previously described. The means for obtaining an air tight seal between the chamber and the piston comprises a rubber washer s provided with a flexible upturned edge t retained in position 95 against the plunger e² by a plate u and nuts v. Above the washer s a quantity of water w is allowed to rest so that when the air from the bottle passes into the upper part of chamber e the pressure on the water forces 100 the flexible edges of the washer against the side of the cylinder, thus obtaining an air tight seal. The capacity of the chamber is regulated by turning the milled nut e⁴, which is capable of independent rotation apart 105 from the cylinder e, the latter being thereby raised or lowered as desired, or it may be regulated as before described by rotating the chamber around the supporting stem e³ in which case the milled nut would be dispensed with. The water w is automatically supplied to the chamber as follows, a bottle is fitted in the holder and the regulating chamber placed in such position that its capacity is greater than that required to hold the air 110 discharged, the water rushes up the hollow stem e³ into the chamber. The supply being cut off, the bottle is removed, and any excess water above the top of the stem e³ runs back to the filling head, leaving only just sufficient to enable a seal to be made.

If a more simple construction is desired, the regulator may be formed in a similar manner to the well-known Stauffer lubricator, so that when the cylinder is raised the 115 capacity of the vessel is increased and vice versa, suitable means being provided to insure an air tight joint between the plunger and cylinder.

The screw down valve d² above referred to, 130

connecting the regulating chamber to the filling head is so arranged that if only a small bottle is being filled, it may be entirely closed, and when larger bottles are being filled the 5 rate of the flow may be regulated by opening or closing such valve.

The operation of the device is as follows, presuming the bottle to be in a particular "filler", the rotation of the table A¹ brings 10 the cam plate p into contact with a roller, or like part x, carried by the frame A³ of the machine, which is thereby rotated and causes the roller o, carried by the cam plate, to press on the lever k resting on the valve 15 spindle m, whereby the same is depressed and the valve opened, the water under pressure enters the bottle in a swirling motion, the air displaced from the bottle passes through the stop down valve d² through the 20 hollow supporting stem e³ into the top part of the regulating chamber e, the capacity of which has been previously determined, when the pressure of air in the regulating chamber equals that of the inflowing liquid, 25 filling ceases, and by this time the table has rotated to a point where the cam plate P of the particular filler is again partly rotated by coming into contact with a further part x¹ carried by the frame A³ of the machine, causing 30 the valve to close and cut off the supply of fluid, the bottle may then be removed and stoppered in the usual manner.

In order to prevent the outrush of air from the regulating chamber splashing the 35 contents of the bottle over when the same is being removed from the holder, a small nipple y is secured in the lower end of the air pipe in the discharge head, such nipple being provided with a series of radial open- 40 ings z so arranged that the air on being discharged is thrown out against the walls of the discharge head instead of directly into the bottle as heretofore.

What we claim is:—

45 1. In a machine for filling bottles with aerated water and the like having a series of filling heads and bottle holders, the combination therewith of means for independently operating and controlling the discharge opening of each filling head and independent means for automatically closing any one or more of such valves should a bottle 50 be broken or a particular filler be vacant, such means comprising for each filler, a cam plate fixed above the filling head, a roller carried by such plate, a cam block or lever upon which such roller bears at predetermined intervals, said cam block or lever being provided with a wedge-shaped slot, a 55 series of levers connecting such cam block or lever with the bottle holder, and a valve spindle sliding in such slot whereby should

a bottle break or a holder be empty the cam block resting on the valve spindle will be withdrawn to such a position that the cam 65 roller will be rendered in-operative as set forth.

2. In a machine for filling bottles with aerated water and the like having a series of filling heads and bottle holders, the combination therewith of means for independently operating and controlling the discharge opening of each filling head, comprising a cam plate fixed to and above the filling head, a roller carried by such plate, a cam block 70 or lever upon which such roller bears at predetermined intervals, said cam block or lever being provided with a wedge-shaped slot, a series of levers connecting said cam block or lever with the bottle holder, a valve spindle sliding in said slot and means carried by the frame of the machine for causing the partial rotation of the cam plates as the machine rotates, whereby the cam block is caused to press on the valve spindle and alternately open and close the valve as set 75 forth.

3. In a machine for filling bottles with aerated water and the like having a series of filling heads and bottle holders, the combination therewith of a regulating chamber 90 comprising a cylindrical chamber, a hollow supporting stem, a fixed plunger carried thereby, means such as a screw thread for raising or lowering the cylindrical chamber 95 on such supporting stem, means carried by the plunger co-operating with means carried by the cylinder for making an air tight joint between the parts, and means connecting the filling head with the regulating chamber 100 as set forth.

4. In a machine for filling bottles with aerated water and the like having a series of filling heads and bottle holders, the combination therewith of a regulating chamber 105 comprising a cylindrical chamber, a hollow supporting stem, a fixed plunger carried thereby, means such as a screw thread for raising or lowering the cylindrical chamber 110 on such supporting stem, means carried by the plunger comprising a rubber washer with a flexible upturned edge, and means for retaining such washer in position, substantially as described.

In testimony whereof we have hereunto 115 set our hands in the presence of two witnesses.
